UNITED STATES PATENT OFFICE.

CHARLES C. WOODWORTH, OF PORTLAND, OREGON.

SAFETY SEAM-RIPPER.

1,081,357.

Specification of Letters Patent. Patented Dec. 16, 1913.

Application filed January 17, 1913. Serial No. 742,673.

To all whom it may concern:

Be it known that I, CHARLES C. WOODWORTH, a citizen of the United States, and a resident of Portland, in the county of 5 Multnomah and State of Oregon, have invented a new and useful Improvement in Safety Seam-Rippers, of which the following is a specification.

My invention relates to safety seam-rippers and its object is to provide a device of 10 this character for cutting or ripping a seam or stitch without liability of injury to the user or to the fabric operated upon.

I shall describe my invention by reference 15 to the drawings which accompany and form a part of this specification and illustrate one embodiment of my invention.

In the drawings, Figure 1 is a front elevation of my improved seam ripper. Fig. 2 20 is a front elevation with certain parts shown in section. Fig. 3 is a plan view and Fig. 4 is a section taken on the line 4—4 of Fig. 1.

Dress-makers and tailors have found that 25 discarded safety-razor blades make efficient seam-rippers, but experience has shown that such a blade cannot conveniently be handled on account of liability of injury to the operator. I therefore provide a handle or 30 holder for a thin highly-sharpened cutting edge, such as a safety-razor blade, and in the particular drawings selected for illustrating my invention, 1 represents a holder having a head 2 which is provided with a longitudinally-extending slot 3 for receiving the 35 blade 4. It has been found advantageous in practice to have the blade adjustable with respect to the head, and, in the present instance as shown, the blade is provided with a longitudinal slot 6 through which passes 40 the thumb-screw 7, the end of which is

threaded in the head as shown at 8. The holder is provided with a curved handle 9 which extends from the head downwardly toward the blade-side of the head. The holder may be of hard rubber, celluloid, or 45 any other suitable material. By reason of the downwardly-extending curved handle, the operator can keep his hand slightly in advance of the cutting edge and also give a rotary motion to the cutter to facilitate 50 the ripping operation. This construction of the handle also permits the work always to be in sight and preserves the cutting edge from injury in case of accidental fall. The shape of the handle results in giving the device 55 a more perfect balance.

It will be understood that various modifications may be made in the particular device described and shown in the drawings without departing from the spirit of my invention. 60

I claim:

A safety seam-ripper comprising a holder having a head provided with a longitudinally-extending open-ended slot, a blade 65 provided with a longitudinal slot, a screw for securing said blade in the slot of said head, said screw passing through the slot in the blade, and a handle for said head, said handle being curved downwardly toward the blade-side of said head and constituting a longitudinal extension thereof. 70

In testimony whereof, I have hereunto subscribed my name this 8th day of Jan. 1913.

CHARLES C. WOODWORTH.
